(57) **CLAIM**

The ornamental design for a radiator hose kit, as shown and described.

DESCRIPTION

FIG. 1 is a rear perspective view of a radiator hose kit showing my new design;

FIG. 2 is a right elevational view thereof;

FIG. 3 is a left elevational view thereof;

FIG. 4 is a rear elevational view thereof;

FIG. 5 is a front elevational view thereof;

FIG. 6 is a top plan view thereof;

FIG. 7 is a bottom plan view thereof; and,

FIG. 8 is a perspective view thereof, wherein the radiator hose kit is shown in the context in which it is intended to be used. The broken lines shown in the figures are included for the purpose of illustrating environment and form no part of the claimed design.
